(57) CLAIM

The ornamental design for a condom ring wallet, as shown and described.

DESCRIPTION

FIG. 1 is a perspective view of a condom ring wallet, illustrated in a closed position, showing my new design;

FIG. 2 is a front elevational view of the invention, illustrated in an open position;

FIG. 3 is a rear elevational view of the invention, illustrated in the open position;

FIG. 4 is a left-side elevational view of the invention, illustrated in the open position, the right-side elevational view being a mirror image thereof;

FIG. 5 is a top plan view of the invention, illustrated in the open position; and,

FIG. 6 is a bottom plan view of the invention, illustrated in the open position.
